METHOD OF AND APPARATUS FOR COMPRESSING AIR AND THE LIKE

Alfred M. Thomsen, San Francisco, Calif.

Application December 18, 1939, Serial No. 309,730

2 Claims. (Cl. 230—69)

(Cl. 230—69)

My invention relates particularly to a method whereby it becomes possible to compress air or other gaseous fluid by the application of heat and not as is now customary by the application of some form of mechanical energy. As compressed air is in itself chiefly utilized as a source of mechanical power, it follows that the production of compressed air by the application of direct heat thereto makes such compression also available as a source of power if taken in connection with a suitable prime mover.

While methods of compressing air and the like by the direct application of heat are old in the prior art, no economic success has been achieved as yet. Faulty apparatus has been largely responsible, but the greatest difficulty consists in getting efficient heat transfer between two gaseous fluids separated from one another by a conducting wall.

To overcome this difficulty I heat the fluid only by direct combustion of fuel therein, in which case a 100% perfect furnace effect is produced. Likewise I cool said fluid only by the instrumentality of direct contact with water, and if this latter medium be maintained at temperatures in excess of 212° F. then, manifestly, such cooling will be accompanied by the generation of the corresponding amount of steam, said steam commingling with the working fluid. To achieve heat economy I avail myself of heat recuperators that function on the well known Stirling cycle.

This is illustrated in Fig. 1 and Fig. 2 which represent in a schematic manner the functions involved in the disclosure. Heating by the combustion of fuel in the fluid and cooling by a water spray are indicated, as is the transfer of a confined body of air, or other gaseous fluid, from a heated to a cooled portion of the confining vessels, and back again, through the instrumentality of the pistons 3 and 4. The moving fluid passes through the indicated regenerators, on which the efficiency of the heat transfer depends, and thus becomes compressed, ultimately flowing into the receivers. Compounding of the effect is indicated by the use of two "units," the working fluid being passed from one to the other. Both figures are explained in greater detail later on.

In the preferred version of my invention as illustrated in the drawings I take advantage of all these innovations, and consideration of the same may therefore be undertaken. I do not necessarily limit myself to the procedure indicated therein but I give it only as a preferred version of the wider scope which appears in my claims.

In the drawings, Figures 1 and 2 illustrate two embodiments of the invention.

In the drawings, Fig. 1, 1 and 2 are a pair of cylinders containing pistons 3 and 4 respectively.

Both ends of each cylinder communicate freely with one another through the recuperators 5 and 6 and the combustion chambers 7 and 8, so that there is substantially the same pressure on both sides of each piston. Such pistons, theoretically, do no actual work but merely serve as the means whereby the working fluid within the cylinders is transferred alternately from one end to the other of the respective cylinder.

- 10 In Fig. 1 both pistons are represented in mid-stroke and the arrows indicate the direction of their travel. 9 and 10 are means for injecting fuel, with auxiliary air if desired, the working fluid within the cylinders being heated by the 15 combustion of said fuel. As the weight of the pistons, with their superimposed burden of water 11 and 12 is considerable, they are advantageously connected and moved in counterbalanced pairs as herein indicated.

20 Any conventional means to move the pistons is evidently applicable, but as the movement of said pistons controls the sequence of effects within the cylinder affected, it can manifestly be supplied from entirely outside sources. This, however, is only a matter of convenience and is not 25 mandatory as each cylinder constitutes a separate entity and the piston could be moved without any regard to sequence with the next in the series, if there be a series and not merely a single 30 unit.

Water sprays 13 and 14 are used on the cool sides of the pistons to control the temperature differential between top and bottom sections of each cylinder, and together with the accumulated water upon the top of each piston they 35 serve to cool the cylinder walls. 15-16-17 represent air receivers connected to the cylinders by pipes as shown, and valves 18-19-20-21 which are actuated by the working fluid and also control 40 the flow of the working fluid, i. e., air undergoing compression, to and from said receivers.

A working stroke consists of the following series of operations. In the cylinder 2 the piston is shown as descending. Such motion transfers the 45 air from the space below the piston to the space above the piston. The displaced air passes upwards through the heat recuperator 5 where it drops much of its heat. The heat not thus absorbed is removed by the water spray 13, by the cooling effect of the water upon the piston, and by the cool walls.

The piston is now at the bottom of its stroke but at some place during the stroke the change in temperature of the working fluid caused a sufficient drop in pressure to actuate the valves 20—21. At the start of the stroke this closed valve 20 and at a later point it opened valve 21' and to equalize the pressure, cool air flowed from the receiver 17 into the cylinder 2.

60 On the upstroke conditions are reversed. The

air above the piston is now to be transferred to the opposite end of the cylinder. In passing through the recuperator much of the stored heat from the former stroke is re-absorbed, and additional heat is supplied by the combustion of fuel injected at 9 and by stored heat in the combustion chamber 7.

When the piston has reached the top of its stroke, substantially all of the working fluid is below the piston for compared to the volume of the cylinder the space within recuperator and combustion chamber is quite small. (For the sake of clarity, the size of recuperator and combustion chamber, relative to that of the cylinder, has been exaggerated.) There has therefore been an increase in pressure according to the law of Charles. This closed valve 21 at the outset, and when the pressure within the cylinder 2 became greater than in the receiver 16, the valve 20 opened and the surplus air and combustion products was discharged into receiver 16.

In the drawings the valves are shown as operated by the change in pressure of the working fluid, but this is only by way of illustration as they could evidently be worked by the engine itself through proper valve motions.

Meanwhile, as pistons 3 and 4 are moving in counterbalance with one another, an identical set of operations has been performed in cylinder 1, and an amount of air equivalent to that which has been transferred from 17 to 16 has also been transferred from 16 to 15, each transfer being at a correspondingly higher pressure. It is self-evident that such compounding, starting with air at atmospheric pressure, can be repeated as long as said air will support combustion of fuel within a highly heated chamber. Even after this point has been reached such compounding can be continued by the use of auxiliary air introduced at 9 together with the fuel supply.

In Fig. 1, only two cylinders are represented, air entering at 22 and being discharged at 23, but it is self-evident that any number of such cylinders could be assembled into a "battery" and that the pressure of the incoming and outgoing air could be adjusted entirely at the will of the operator. Motion to the pistons 3 and 4 is indicated as conveyed through the instrumentality of the rocker arm 26, which in turn is moved by the electric motor 29, the pinion of same, 28, engaging the toothed sector 27 which is attached to the rocker arm. This method of moving the pistons is purely schematic and is not claimed, it being evident that any number of other ways to produce such motion could be substituted.

If the compressed fluid is to be used at once in a prime mover then it will be evident that it would be advantageous to permit the so-called "cool" end of the cylinder to remain at such a temperature that cooling is produced by the conversion of the sensible heat of the fluid into latent heat of evaporation of water. In this case no discharge of water would be required from the cylinder to compensate for that added by the spray but instead steam would be formed and such steam would leave commingled with the working fluid proper, and would in fact become a component thereof. The heat otherwise wasted in the cooling water would thus perform useful work in the prime mover.

It will likewise be evident that the alternate rise and fall of pressure within such a pair of vessels as herein described can be used to impart motion to a piston within an enclosed cyl-

inder by simply connecting the opposite ends of said cylinder with the cooled ends of the respective vessels, thus converting at once the heat energy of the working fluid into mechanical work.

5 This is indicated and illustrated in Fig. 2 of the drawings. The same reference numbers have been used throughout as in Fig. 1, before described, and the entire operation is identical. It will be seen that the cool ends of the respective cylinders, 1 and 2, connect by means of the pipes 32 and 33 with opposite ends of a working cylinder, 31, containing a tight piston 32. As the pressures in 1 and 2, rise and fall alternately they will manifestly impart motion to said piston which can be connected to any type of mechanism for the conveyance of power by its attached piston rod 30. As in the case of Fig. 1, the means by which the pistons 3 and 4 are moved is purely schematic and not claimed, a balance wheel, 26, being substituted for the former rocker arm. Meanwhile compressed air will be vented at the valves 18 and 20, while air will be aspirated at the valves 19 and 21.

Having thus fully explained my process and 25 the types of machinery suitable for use in said process,

I claim:

1. In an apparatus for compressing air by the direct application of heat the combination of a 30 series of units each one of which is operating under different pressure but being otherwise identical and each unit consisting of; a combination of a vessel with a movable separating member dividing same into two parts; a free interconnection between said two parts containing a heat recuperator; means for heating the air at one end of said recuperator by the combustion of fuel therein; means for cooling said air at the opposite end of the recuperator by direct contact with water; suitable valves for the discharge of compressed air and for the admission of fresh air to replace such discharge as the pressure rises and falls in accordance with the motion of the movable member; and, means for imparting motion to said movable member; each unit of 40 said series, except the first and last units of the series, receiving air from the next lower in pressure of the series and discharging air to the next higher in the series; additional means being supplied for the introduction of auxiliary air of combustion where needed.

2. The method of compressing air by the direct application of heat which comprises; transferring a confined body of said air alternately 45 from a heated to a cooled portion of the confining vessel; storing a part of the heat resident in the hot air in its passage to the cool portion of said vessel and returning said heat again to the air in its return travel to the former location; adding additional heat to said air by burning fuel therein at the hot end and converting the residual heat in said air into latent heat of evaporation of water by direct contact with water at the cool end, said water being maintained at 50 temperatures in excess of 212° F., cooling thus being effected by conversion of the sensible heat in the working fluid into latent heat of evaporation while the steam thus being continuously formed escapes as a component of the working fluid; meanwhile venting air under pressure and admitting fresh air to take its place, alternately, as the pressure rises and falls on each alternate transfer.
